UNITED STATES PATENT OFFICE

ALFRED J. FLAUDER, OF TRUMBULL, CONNECTICUT, ASSIGNOR TO THE WEIDLICH BROS. MFG. CO., OF BRIDGEPORT, CONNECTICUT, A CORPORATION OF CONNECTICUT

DESIGN FOR A BOTTLE OPENER

Application filed June 22, 1932. Serial No. 44,165. Term of patent 7 years.

To all whom it may concern:

Be it known that I, ALFRED J. FLAUDER, a citizen of the United States, and a resident of Trumbull, in the county of Fairfield and State of Connecticut, have invented a new, original, and ornamental Design for Bottle Opener, of which the following is a specification, reference being had to the accompanying drawing, forming a part thereof, and in which:—

Fig. 1 shows a front view of my new and original design for bottle opener;

Fig. 2 shows a rear view of the same; and Fig. 3 is a central vertical longitudinal section of the same, the corkscrew portion broken away, and taken on line 3—3 of Fig. 1.

I claim:

The ornamental design for a bottle opener, substantially as shown and described.

Signed at Bridgeport, in the county of Fairfield and State of Connecticut, this 20th day of June, 1932.

ALFRED J. FLAUDER.
